UNITED STATES PATENT OFFICE.

EDWARD B. KOPLITZ, OF HOBOKEN, NEW JERSEY.

BOX-COVER FASTENER.

Application filed May 11, 1927. Serial No. 190,565.

This invention relates to new and useful improvements in corrugated paper boxes, or like receptacles, and has particular reference to the lids and manner of attaching the same to the receptacles.

In the use of tall receptacles which are made of corrugated paper, and which have the ends removable, great difficulty has been experienced in properly securing such ends within the receptacles. Ordinarily gummed paper strips are used to secure the ends to the sides of the receptacles, but this is difficult of accomplishment, due to the fact that no adequate means are provided for supporting the end, within the receptacle.

The principal object of the present invention is to provide a novel means for supporting the end of a receptacle, of the character named, within the receptacle, and a locking means, associated with the supporting means, for holding the end in proper position, against unauthorized removal, it being necessary to destroy the end before it can be removed.

Another object is to provide a supporting and locking device of this character, which is simple in construction, inexpensive to manufacture, and which can be readily applied to boxes, of this character, now in use.

Other objects and advantages will be apparent from the following description when taken in connection with the accompanying drawings.

In the drawings:

Figure 1 is a perspective view of one end of a receptacle, showing the use of the improved fasteners.

Figure 2 is an enlarged vertical central sectional view through one of the fasteners, and the associated portions of the receptacle side and end.

Figure 3 is a perspective view of the box attaching portion of the fastener removed from the box.

Figure 4 is a perspective view of the locking member of the fastener.

Figure 5 is a vertical sectional detail view on the line 5—5 of Figure 3.

Referring particularly to the accompanying drawing, 10 represents the upper portion of a corrugated paper receptacle, which is polygonal in shape, the upper end of each side of the receptacle being turned downwardly into the receptacle, in the form of tabs, as shown at 11. The cover, or end 12, is made up of a plurality of layers of cor-

rugated paper and having its periphery cut to properly fit within the end of the receptacle, and press said tabs against the inner faces of the said sides.

Secured to a number of the said tabs 11 are the metal plates 13, each of which is formed with the tangs 14, piercing the tab and clinched on the opposite side thereof. The opposite vertical edges of the plate 13 are bent outwardly to form the flanges 15, while the lower end of the plate is bent to extend horizontally, as at 16, from the body of the plate. In the intermediate portion of plate 13, and near the lower end thereof, there is formed a vertical elongated opening 17, and in the intermediate portion of the inner edge of the flange 16 there is formed a notch registering with the lower end of the said opening 17. On this ledge, or flange 16, the end or cover 12 rests, as clearly seen in Figures 1 and 2, of the drawing.

After the cover has been properly placed within the end of the receptacle, so that it rests on the ledges 16, of the plates 13, the locking member, represented as a whole by the numeral 18, and as shown specifically in detail in Figure 4, is properly inserted. This locking member 18 comprises a body portion 19, of a width to properly fit between the flanges 15, of the plate 13, and has the outwardly turned finger-grip 20, on its upper end, which is grasped by the operator to manipulate the member into locking position. Extending centrally from the lower end of the body 19 is an elongated and pointed tongue 21, and intermediate the length of the tongue there is struck out an upwardly and outwardly inclined tab 22. The body of the plate 19 is cut upwardly, from the lower edge, on lines 23, which are continuations of the sides of the tongue. It will be particularly noted that the tongue is bent backwardly to a slight degree whereby to exert a spring action against the outer face of the plate 13, and to better engage the tab or detent 22 with the down-turned portion of the flange 16, shown at 23, and which tab results from the formation of the slot 17.

In the operation of the invention, the cover or end is slipped into the end of the receptacle until it rests on the ledges 16, of the plates 13. The operator, being provided with a number of the locking members 18, inserts the tongue 21 of one of said locking members in the slot 17, of one of the plates 13, and forces said tongue downwardly through the said slot

until the detent 22 snaps beneath the lower edge of the tab 23, thus firmly locking the member 18 to the plate 13, while at the same time the finger-grip 20 engages on the upper face of the cover or end and holds the latter against upward movement. The operator inserts a locking member 18 in each of the plates 13, thus securely fastening the cover or end within the end of the receptacle.

10 While I have shown the invention as applied to a receptacle having twelve sides, I wish it understood that the fastener may be used with a receptacle of any number of sides. In fact the device is capable of use in connection with cylindrical receptacles of the barrel type, with equal facility and effectiveness.

Attention is directed to the fact that when the locking members 18 have been properly inserted, and engaged with the cover or end of the receptacle, such members cannot be removed without destroying the end, or portion of the side of the receptacle, thus rendering the device proof against theft. Furthermore, all danger of the end being accidentally displaced is obviated.

What is claimed is:

1. The combination with a receptacle and the end closure thereof, of a bracket secured 30 within the receptacle for supporting the closure within the receptacle, and a locking member arranged to be inserted between the bracket and the closure and having means engaging with the closure for holding the 35 same on said bracket.

2. The combination with a receptacle and

the end closure thereof, of a bracket secured within the receptacle and having a flange for supporting the closure within the receptacle, said bracket having an opening between the receptacle and the periphery of the closure, and a locking member insertable through said opening and having interlocking engagement with said bracket beneath the closure and holding engagement with the upper portion of the closure. 45

3. The combination with a receptacle and the end closure thereof, of a plate secured within the side of the receptacle, said plate having an opening and a horizontal ledge, 50 said ledge being arranged to support the closure, and a locking member having a tongue arranged to be inserted between the plate and closure and through said opening and interlocking with said plate, and having 55 holding engagement with the closure.

4. The combination with a receptacle and the end closure disk thereof, and the inwardly folded tabs, of a metal plate secured to a tab, within the receptacle, said plate having a 60 horizontal flange for supporting the said closure in proper position within the receptacle, said plate having an elongated opening and a terminal notch, and a locking member having a tongue inserted in said opening and 65 notch and having a detent for locking engagement with the plate, said locking member having a flange arranged to bear on the upper face of the closure to hold the same on said horizontal flange. 70

In testimony whereof, I affix my signature.

EDWARD B. KOPLITZ.
